UNITED STATES PATENT OFFICE.

JULIUS ADERER, OF NEW YORK, N. Y.

PLIERS.

1,141,916.

Specification of Letters Patent.

Patented June 8, 1915.

Application filed August 28, 1913. Serial No. 787,079.

To all whom it may concern:

Be it known that I, JULIUS ADERER, a citizen of the United States, residing in the borough of Manhattan, city, county, and State of New York, have invented certain new and useful Improvements in Pliers, of which the following is a specification.

This invention relates to pliers, and has for an object to provide an instrument for bending a flat bar in the plane of its flatness by applying force edgewise to the bar at a plurality of places and during the bending, preventing the twisting of the bar. This improvement is particularly useful in dentistry, especially for bending lingual bars.

One object of the invention is therefore to provide lingual bar-bending pliers.

In the drawings accompanying this specification one practicable embodiment of the invention is illustrated.

In the drawings, Figure 1 represents in perspective a pair of pliers applied to a bar which is being subjected to the bending operation; Fig. 2 is a cross-section of a bar and a longitudinal section of one of the beaks; Fig. 3 is a view similar to Fig. 2 but showing a bar of different formation; and Fig. 4 is an end view of the pliers in the Fig. 1 position.

In the drawings the illustrative pair of pliers is shown provided with a pair of jaws 1 and 2 having handles 3 and 4 respectively. The jaw 1 is shown provided with a pair of spaced apart beaks 5 and 6, and the jaw 2 is shown provided with a single beak 7 located in such a position that it may normally pass into the space 12 between the beaks 5 and 6. Compared with the space 40 between the beaks 5 and 6, the beak 7 is relatively narrow. The beaks 5 and 6 are sufficiently widely separated that when the beak 7 passes into the space 12 there will be a constant wide clearance between the sides of beaks 5 and 6, and the adjacent sides of the beak 7.

Each of the beaks is shown provided upon its working face, which is its free end in the illustration, with work engaging means in the form of the walls of a V-shaped notch or socket 8 for receiving the bar 9 during the bending operation. The work engaging sockets are shown alined. Side faces 10, 10 of the sockets 8 are disposed in such relative positions one to the other, and the beaks are also relatively disposed that the bar 9

is engaged on the sides 11, 11 adjacent its edges and inwardly thereof, and thereby prevented from twisting when force is applied. The beak 7 will act upon the bar at a 60 position midway of the beaks 5 and 6, and will exert its bending pressure in its movement toward the space 12 between the beaks 5 and 6 in the direction of the longest axis, represented by 13 in Fig. 2, of the bar. It 65 will thus be seen that the spaced apart beaks of one jaw engage the sides of the flat bar at one edge, and the other beak engages the sides of the bar at the other edge and thus prevent twisting of the bar during the bending operation. The beaks 5, 6 and 7 engage the bar at three widely separated positions 70 longitudinally of the bar.

By means of the present improvement a flat bar is readily bent in the plane of its 75 flatness without any twisting whatsoever. These pliers are useful in many employments, but are particularly useful in bending the lingual bar, which is frequently an oval or flat wire, into shape without leaving 80 marks upon it. This is essentially a hand tool and is used by the dentist for fitting a lingual bar to the mouth of an individual patient. This work is frequently, owing to the well known difficulties under which the 85 dentist must needs operate, a series of fittings and bending, little by little, sometimes not enough, sometimes too much at one point, requiring bending the bar back to 90 overcome the excessive bend. The bar during this bending and trying is several times released from the pliers and returned to them. The bar after these bendings and rebendings retains its original cross sectional formation and all parts remain in the 95 original plane. Various gages of wire are employed in this class of work and these pliers will accomplish satisfactory results when used on any of the various sizes. The jaws and beaks need not be separable and 100 interchangeable, since the various sizes or gages will respond satisfactorily to a single instrument. The beaks, jaws and handles may therefore be made in one piece, lessening the cost of the instrument and simplifying the work of the user. An instrument thus constructed is capable of bending, in 105 the plane of their flatness, flat lingual bars of different thicknesses and supporting such bars against lateral twisting movement.

Fig. 3 shows a flat bar 14 in position in the jaw, such bar having square corners 15.

In this example the bar is engaged at both sides at the edge. The impingement of the faces 10 of the socket upon the corners will effectively prevent the bar from twisting 5 while being bent in the direction of its longest axis illustrated in this view by 16.

Although but one embodiment of the invention is shown, it will be apparent that this is illustrative of the invention, and that 10 changes may be made within the scope of the claims without departing from the spirit of the invention.

Having described my invention I claim:—

1. Pliers for bending flat bars in the plane 15 of their flatness, and comprising a pair of pivotally connected jaws, one of these having a relatively narrow beak provided with a work engaging V-shaped notch, and the other having two beaks, located in position 20 for the other beak to pass into the space between them with a constant wide clearance between the adjacent sides of the beaks, and each provided with a work engaging V-shaped notch alined with the notches on the 25 other beaks.

2. Pliers for bending flat bars in the plane of their flatness wherein one jaw is provided with a pair of spaced apart beaks, each having means for engaging both sides 30 of a flat bar at one edge or inwardly thereof

for preventing twisting of the bar during the bending operation, the other of said jaws being provided with a relatively narrow beak movable into the space between the beaks of the said pair with a constant wide 35 clearance between the adjacent sides of the beaks, and having means alining with the engaging means of the pair of beaks for engaging both sides of the said bar at the other edge or inwardly thereof for preventing twisting of the bar during the bending operation.

3. Lingual bar bending pliers having two jaws, one of said jaws being provided with a relatively narrow beak and the other of 45 said jaws being provided with a pair of beaks located in position for the beak on the other jaw to pass into the space between them with a constant wide clearance between the adjacent sides of the beaks and each of 50 said beaks being provided with alined notches for engaging bars of various thicknesses for preventing lateral twisting of the bar during the bending of the same in the plane of its flatness.

JULIUS ADERER.
